(57) **CLAIM**

The ornamental design for a cushion structure for packing, as shown and described.

DESCRIPTION

FIG. 1 is a perspective view of a cushion structure for packing showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the cushion structure for packing in another usage state;

FIG. 10 is a flat unfolded view thereof;

FIG. 11 is a bottom front perspective view of the assembled cushion structure for packing, shown in use with an exemplary notebook computer;

FIG. 12 is a bottom rear perspective view thereof;

FIG. 13 is a top perspective view of the cushion structure for packing as shown in FIG. 1, shown in use with another exemplary cushion structure for packing, as well as an exemplary packing box;

FIG. 14 is another top perspective view thereof, showing both the cushion structure for packing as well as the exemplary cushion structure for packing in another usage state;

FIG. 15 is an exploded view of FIG. 13; and,

FIG. 16 is an exploded view of FIG. 14.

The dashed broken lines in FIGS. 11-16 are for the purpose of depicting environment and form no part of the claimed design.

1 Claim, 13 Drawing Sheets
